UNITED STATES PATENT OFFICE.

ARTHUR P. PAINE, OF NEW HAVEN, CONNECTICUT, ASSIGNOR TO WINCHESTER REPEATING ARMS COMPANY, OF NEW HAVEN, CONNECTICUT, A CORPORATION OF CONNECTICUT.

DESIGN FOR A BATTERY HAND-LAMP.

55,571.

Specification for Design.

Patented June 29, 1920.

Application filed April 2, 1920. Serial No. 370,891. Term of patent 14 years.

To all whom it may concern:

Be it known that I, ARTHUR P. PAINE, residing at New Haven, Connecticut, have invented a new, original, and ornamental Design for a Battery Hand-Lamp, of which the following is a specification, reference being had to the accompanying drawing, forming a part thereof.

The drawing is a perspective view of a battery hand lamp showing my new design.

The cylindrical casing 1, bottom cap 2

and front ring 3 are of metal, preferably nickelated, and there is a glass lens or bull's-eye 4 at the front end of the battery hand lamp.

I claim:

The ornamental design for a battery hand lamp substantially as shown and described.
